His Attorney.

UNITED STATES PATENT OFFICE

2,103,905

TURBINE BUCKET WHEEL NOTCH BLOCK

Rudolph Hillner, Schenectady, N. Y., assignor
to General Electric Company, a corporation
of New York

Application January 4, 1936, Serial No. 57,593

2 Claims. (Cl. 253—77)

The present invention relates to bucket wheels such as are used in elastic fluid turbines for transforming thermodynamic energy of steam or like elastic fluid into mechanical energy. The invention relates more specifically to the kind of bucket wheels which comprise a disk element and a row or rows of buckets secured to the disk element by a dovetail connection between a base portion of each bucket and the rim of the wheel. 5 In the usual arrangement of this kind, shoulder portions of the dovetail-forming rim portion are cut away to define a notch opening through which the buckets are inserted and slid along the rim during assembly. Difficulties are experienced 10 in closing these notch openings by means of a notch opening bucket or a notch opening block in order to prevent relative movement of the buckets on the rim, and lock them in place and also in order to fill out the contour of the wheel. 15 In modern high speed turbines where the buckets are subjected to considerable centrifugal forces, it is sometimes undesirable to insert in the notch opening a bucket because of the great centrifugal forces and, in many cases, it is not even desirable 20 to put into the notch opening a heavy block or filler. 25

The object of the present invention is to provide an improved construction and arrangement of bucket wheels of the type above referred to 30 whereby the buckets are rigidly secured to the rim of the disk and prevented from relative movement thereon.

For a consideration of what I believe to be 35 novel and my invention, attention is directed to the following description and claims appended thereto in connection with the accompanying drawing.

In the drawing, Fig. 1 illustrates an exploded, 40 perspective view of a bucket wheel portion embodying my invention; Fig. 2 is an enlarged, sectional view through the notch opening of the bucket wheel shown in Fig. 1; and Fig. 3 is a perspective view of the assembled bucket wheel.

The arrangement comprises a disk or disk 45 member 10 having a grooved rim portion defining a dovetail 11. The dovetail of the rim forms shoulders 12 and 13 which are partly cut away to form a notch opening 14 (Fig. 1). Buckets 15 comprising blades 16 and base portions 17, which latter define inverted dovetails, are inserted 50 through the notch opening and slid to the left or right along the rim of the wheel. In order to prevent relative movement between the row of buckets and the disk, a forked member or fork 55 18 is provided in the notch opening, which mem-

ber has legs 19, 20 straddling the rim and filling the cut-away shoulder portions thereof. This fork or filling member in accordance with my invention is securely attached to the rim and prevented from radial movement due to the action of centrifugal force exerted thereon by means of two grub screws, bolts or like locking means 21, 22. In order to distribute the forces exerted on the grub screws or bolts substantially along their entire length threaded bores 23, 24 10 are formed in the adjacent portions of the rim and the fork 18 for engaging the screws.

During manufacture and assembly the buckets with their bases are slid along the rim of the disk. After all the buckets have thus been assembled on the disk, the fork 18 is inserted in the notch opening and thereafter the threaded bores 23, 24 are formed so that one half or side of the lower part of each bore is defined by the fork and the other half by the rim. Finally, the grub screws which in substance represent radially inserted locking members are screwed into the threaded bores thus formed and locked in position by peening over portions 25 (Fig. 2) on the outer surface of the fork to engage the rounded 15 heads of the screws. The outer ends of the bucket blades are held together in known manner by a shroud band 26 (Fig. 3).

With my invention I have accomplished a simple arrangement for closing notch openings of bucket wheels by means of a forked member and holding such member securely in position, thus preventing it from movement by high, centrifugal forces exerted thereon. The arrangement is reliable in operation and may be manufactured at 30 comparatively low cost. The forked element is held by the screws with sufficient strength to 35 permit in certain cases the provision of said element with a bucket blade.

Having described the method of operation of my invention, together with the apparatus which I now consider to represent the best embodiment thereof, I desire to have it understood that the apparatus shown is only illustrative and that the invention may be carried out by other means. 40

What I claim as new and desire to secure by Letters Patent of the United States, is:

1. A bucket wheel comprising a disk member having a rim and a row of buckets having bases forming a dovetail connection with the rim, a 50 portion of the rim being cut away to form a notch opening through which the buckets are inserted during assembly, means for closing the notch opening to prevent relative movement between the disk member and the buckets, said means 55

comprising an element having legs straddling the rim and disposed in the notch opening and grub screw means secured in threaded radial bores formed in adjacent portions of the rim and the 5 legs, and means to prevent loosening of the grub screw means.

2. A bucket wheel comprising a disk member having a rim and a row of buckets having bases forming dovetail connections with the rim, a portion 10 of the rim being cut away to form a notch opening through which the buckets are inserted

during assembly, a forked member having legs straddling the rim and filling the notch opening, radial bores being formed between adjacent portions of the legs and the rim, grub screws disposed within the bore to secure the fork to the 5 rim, and means holding the grub screws in position, outer portions of the forked member near said bores being peened over to hold the grub screws in position.

RUDOLPH HILLNER. 10
